(57) **CLAIM**

The ornamental design for a display panel or screen with animated graphical user interface, as shown and described.

DESCRIPTION

FIG. 1 is a front view of a display panel or screen with a first image of an animated graphical user interface showing our new design;

FIG. 2 is a front view thereof with a second image; and, FIG. 3 is a front view thereof with a third image.

The even dash broken lines illustrating portions of graphical user interface form no part of the claimed design. The dot-dash broken lines define the bounds of the claimed design and form no part thereof. In FIGS. 1-3, the portions outside the dot-dash broken lines are claimed and the portions inside the dot-dash broken lines are not claimed. The appearance of an image sequentially transitions between FIGS. 1-3. The process or period in which an image transitions to another forms no part of the claimed design.

1 Claim, 3 Drawing Sheets
